C. T. Reed

Attorney

UNITED STATES PATENT OFFICE.

HERBERT H. REED, OF COVINGTON, OHIO.

SPOTLIGHT-HANGER.

1,377,927.

Specification of Letters Patent. Patented May 10, 1921.

Application filed December 15, 1920. Serial No. 430,814.

To all whom it may concern:

Be it known that I, HERBERT H. REED, a citizen of the United States, residing at Covington, in the county of Miami and 5 State of Ohio, have invented certain new and useful Improvements in Spotlight-Hangers, of which the following is a specification.

This invention relates to dirigible head 10 lights for motor vehicles, and pertains especially to devices for hanging or suspending and manually operating spot lights.

The object of the invention is to provide, in a holder or hanger, novel and peculiar 15 manually-operated means for turning a spot light horizontally in the plane of an arc of a circle, and for swinging the turnable member in an arc of a circle perpendicular to the plane of movement of the turnable member.

A further object of the invention is to provide, in a spot light fixture, such connections between a hand-operated shaft and the turnable member of a spot light bracket 25 as to afford means for turning and setting said member, and means for swinging and setting said member by turning the shaft.

A still further object of the invention is to provide novel and peculiar arrangements 30 of spiral springs for holding the movable parts of a spot light hanger in turnable and swingable positions so as to fix the light at various angles and in various positions as desired.

35 Various other objects, advantages and improved results are attainable in the manufacture and practical working of the invention, as will be hereinafter disclosed.

In the accompanying drawings forming 40 part of this application:

Figure 1 is a side elevation of the front part of an automobile showing the application of the invention.

Fig. 2 is a top view of the hanger, the 45 dotted line A indicating the turning movement.

Fig. 3 is a front view of the hanger, the dotted line B indicating the swinging movement.

50 Fig. 4 is a longitudinal sectional view taken through the hand shaft sleeve.

Fig. 5 is a perspective view of part of the hand shaft and certain of its mountings.

Fig. 6 is a detail view of a modification. 55 The same reference characters denote the

same parts throughout the several views of the drawings.

In carrying out my invention, which is applicable to the usual standard as 1, or to the wind shield post of an automobile for 60 suspending the usual lighting device commonly called "spot light," I employ a bracket comprising a plate member 2 adapted to be secured to the standard 1, and having a forwardly extending wing 3 projecting from the plate member at right angles thereto. A yoke 4, in which a turnable member 5 is journaled, has a stem 6 projecting therefrom and extending through the wing 3 in which the stem is journaled 65 or turnably secured, and said stem is provided with a spacing sleeve 7 between the wing and the yoke. The turnable member 5 is adapted to have the spot light fixture 70 as 8 attached thereto, and said member has 75 an extended journaled or pintle end 9 to which is attached an arm 10 having a ball and socket connection 11 with one end of a connecting rod 12. The member 5 and the stem 6 are turnable in planes perpendicular 80 to each other by means of a hand-operated shaft 13 having a fixed collar 13^a and having its forward end screw threaded for a block head 14, which has a lever 15 pivoted thereto as at 16 and depends therefrom 85 through the end of the stem 6, so that by turning the shaft, which is provided with a suitable hand wheel 17, the head is moved longitudinally on the shaft and causes the lever 15 to swing or turn the stem 6 to such 90 positions possible for said movement as desired for the spot light. A coil spring 18 on the stem 6 between the wing 3 and a washer 19 abutting against the lever 15 for holding the stem in such various positions 95 as it may be placed by turning the hand shaft.

The hand shaft works through a sleeve 20, the outer end of which has a handle 21 for turning the sleeve on said shaft without 100 turning the shaft, and the sleeve works through the bracket member 2 where this end of the sleeve has a crank lever 22 secured thereto and working between the collar 13^a and the member 2, and the lever 22 105 is connected with the connecting rod 12 by a ball and socket joint as 23. A spiral spring 24 is mounted on the sleeve 20 and has one end attached to the head 25 of the handle 21 for holding the sleeve 20 and its connected 110

elements in such various positions as placed by turning the sleeve.

Referring to the modification shown in Fig. 6 of the drawings, the bracket members 26 and 27 which embrace a wind shield post as 28, are clamped by a suitable bolt 29, and one of said members has a leg 30 engaging the other member, while the operating mechanism is the same as that hereinbefore described.

Obviously various other applications may be made of the invention, therefore I do not wish to limit myself in its application, neither do I wish to be understood as confining myself to any particular material and size, but reserve the right to make such changes and variations in the manufacture and practical utility of the invention as may come within the scope of the appended claims.

Having thus described my invention what I claim as new and desire to secure by Letters Patent is:

1. In a device of the type described, a light-fixture member, a yoke for mounting said light-fixture member, a stem projecting from said yoke, said stem and light-fixture member being turnable in planes perpendicular to each other, a sleeved hand-operated shaft, a block-head member having a screw-threaded connection with said shaft, a lever-connection between said block-head and said stem for actuating the light-fixture member, and means for actuating said light-fixture member from the sleeve of the hand-operated shaft.

2. In a device of the type described, a light-fixture member, a yoke for mounting

said light-fixture member, a stem projecting from said yoke, said stem and light-fixture member being turnable in planes perpendicular to each other, a hand-actuated shaft having a fixed collar thereon, a block-head actuated by said shaft and having a lever pivoted thereon and depending therefrom through the end of the stem, a resilient member and a washer arranged upon said stem adapted to deliver pressure upon said lever to hold said stem in variously adjusted positions, and means for actuating said light-fixture member from the sleeve of said hand-operated shaft.

3. In a device of the type described, a light-fixture member, a yoke for mounting said light-fixture member, a stem projecting from said yoke, said stem and light-fixture member being turnable in planes perpendicular to each other, a hand operated shaft, a tubular member sleeved upon said shaft, a block-head member having a screw-threaded connection with said shaft, a lever-connection between said block-head and said stem for actuating the light-fixture member, said light-fixture member having a pintle, a crank-lever connection with said tubular member, and a ball and socket and crank connection between said crank-lever connection and said light-fixture member pintle.

In witness whereof I hereunto set my hand in the presence of two witnesses.

HERBERT H. REED.
